FURNACE LINING

George F. Doyle and Theodore Kauffman, Jr.,
Chicago, Ill., assignors to The S. Obermayer Co.,
Chicago, Ill., a corporation of Ohio

Application February 3, 1933, Serial No. 654,999

7 Claims. (Cl. 72—101)

Our invention relates to plastic lining for furnace walls, roofs, and the like, and has for its principal object the provision of a novel means of anchoring an originally plastic lining material to the supporting structure of the furnace.

In furnace walls, it is necessary to provide an interior portion of refractory material. The anchoring of the refractory walls to the outer retaining walls has always been a difficult problem. 10 in the construction of boiler settings no matter what refractory is used. With an originally plastic refractory material, the matter of mounting or anchoring the plastic portion of a wall to the supporting structure or retaining wall has here- 15 tofore been solved with limited success by utilizing metallic tie-members one end of which is fastened in the retaining wall, and the hook-like other end is projected into the plastic refractory wall.

20 Some of the difficulties encountered in this type of structure are that the coefficient of expansion of the metal anchor is much greater than that of the plastic fire brick so that the anchor is liable to rupture the fire brick. Also, the metallic anchor cannot be projected to the furnace face of the plastic wall, and the fire receiving portion of the wall is not anchored. Again, the metallic anchors lose their strength at relatively low temperatures, and in fact they cannot be used in cer- 25 tain sections of the wall because of the danger that they may melt and wash out the surrounding refractory.

Our invention contemplates the provision of an anchor having substantially the same coefficient of expansion as the plastic refractory, in fact we 30 preferably provide an anchor which is pre-fired and is made from the same material as the plastic lining.

Our invention also contemplates the provision 35 of an anchor which may be brought out flush with the hot face of the plastic lining.

Our invention further contemplates the provision of an anchor tile which may be always adjusted to the thickness of the wall whether it be 40 full nine inch, seven inch, or a five inch wall without the necessity of carrying stocks of different sizes of anchors. That is, we provide an anchor tile the length of which is sufficient to allow it to come flush with the hot face of a plastic wall 45 nine inches thick, and so construct this tile that it may be readily broken off to reduce its length to make it fit either a seven inch or a five inch thickness of wall.

Our invention further contemplates the provision 50 in an anchor tile of means whereby a single

tile may be used for a full nine inch wall or broken in two and both ends used for a thinner or half thickness wall.

Our invention further contemplates the provision of a novel method of applying the anchors 60 to a plastic lining.

Other and more detailed objects of our invention are the provision of a novel means of supporting the plastic lining sectionally and the provision of a novel means for utilizing the originally 65 plastic refractory for arches or roofs of furnaces.

We will describe the preferred form of our invention by reference to the accompanying drawings wherein—

Fig. 1 is a transverse section through the side 70 wall and roof of a furnace;

Fig. 2 is a detailed section on the line 2—2 of Fig. 1;

Figs. 3, 4, 5, 6, and 7 are detailed sections illustrating the several steps in applying the anchor 75 tile to the plastic refractory lining;

Fig. 8 is a perspective partly in section of one of the anchor tile; and

Fig. 9 is a perspective of a metallic form used in 80 applying the walls.

Referring now in detail to the drawings, we have shown the retaining wall of the furnace at 10 as being constructed of common brick although it is obvious that a structural wall may be used equally as well.

The beams 11 form the means for suspending the roof 12 over the furnace, this roof being of originally plastic refractory material. The side wall of the furnace is shown as lined with an originally plastic refractory material at 13. The means for anchoring the plastic lining to the retaining wall consists of the anchor tile 14, 15, 16, and suitable lag screws such as 17 or bolts 18. We have indicated in Fig. 1 the plastic lining as 90 being supported sectionally by means of the longitudinally running beam 19 and its shelf 20 of fire brick so as to relieve the plastic lining of excessive load where the furnace wall is high.

The anchor tile 14 is shown in full size in perspective in Fig. 8 and is preferably made of the 100 same plastic refractory material as the lining 13, but is pre-cast and pre-fired at high temperature to insure great strength.

By the term pre-cast we mean formed into a definite shape before being inserted into the wall 105 lining regardless of the method of producing this shape. Constructing the anchor tile of the same material insures equal expansion and contraction of the lining and anchors. It also avoids the danger of the anchor melting due to excessive 110

temperature and permits the anchoring means to extend right out to the hot face of the lining thus leaving no part of the plastic lining without an anchor. The tile 14 is preferably made in a size 5 slightly less than nine inches long so that it may anchor a wall of a thickness equal to the length of the standard fire brick.

It will be noted that the tile is weakened as indicated at 21, 22, and 23 by transversely run-

10 ning grooves leaving the projections intermediate the grooves to facilitate the holding of the lining by the tile. Because of this design, the entire nine inch lining is anchored at three different thicknesses: first at the hot face of the lining, 15 and again about two inches from the hot face, and a third time at least five inches in from the hot face.

It is customary in many instances to have the thickness of the lining decrease toward the top 20 of the furnace, and this is shown clearly in Fig. 1. It will be noted in Fig. 1 that the anchor tile 14 is used in its entire length. The anchor tile 15 is broken off to a seven inch length so that it still comes out to the face of the wall while the 25 anchor tile 16 at the top is only half the original length. The anchor tile is slotted at both ends as indicated at 24 and 25 to receive the heads of the lag screws or bolts, the slots 24 and 25 being T-slots as shown most clearly in Figs. 2 and 8. 30 This makes it possible to use both ends of the nine inch anchor by breaking it in the middle.

The method of applying the plastic lining will now be described by reference to Figs. 3 to 7 and Fig. 9. The lag screw 17 or other suitable anchoring means is first embedded in the retaining wall brick work, and this anchor should be long enough so that it will be firmly anchored in the second course of the brick leaving the head about two inches from the brick work. The plastic 40 refractory is then built up as indicated at 13 in Fig. 4 so that it is even with or slightly above the lag screw. The cast iron form 26 shown in detail in Fig. 9 is then placed on the plastic material 13 and pounded down in place to make an 45 impression to receive the anchor tile. The plastic lining is usually pounded in place, and, by the use of this form to make an impression for the anchor tile, we make sure that the plastic material will be fitted up tightly in the grooves of the 50 anchor tile without pounding the tile itself which would cause considerable breakage thereof. The anchor tile 14 is then placed in position as shown in Fig. 6, and the hole around the lag screw head is preferably filled with a suitable heat insulating 55 material to act as an insulator and also as a bearing surface between the lag screw head and washer and the anchor. If it is desirable to allow for differences in expansion and contraction between the lining and the retaining wall, a yielding insulating packing may be used around the lag 60 screw head thus allowing sufficient movement between the lag screw head and the anchor in a vertical direction or a direction lengthwise of the wall to avoid any undue strain.

65 After the anchor is in place, the wall may be built up further as indicated in Fig. 7, and, if a substantial thickness of the plastic material is placed over the anchor before it is rammed or pounded down, the tile will not be injured. In 70 case of walls say five inches thick instead of nine inches, the anchor tile may be broken at the groove 22 to give two anchors instead of one, the T-slots 24 and 35 providing for securing them to the retaining wall.

75 In the case of high furnace walls, the longi-

tudinally running beams 19 may be mounted in place with suitable supports before the plastic lining is applied, and the short anchor tile such as 27 may be secured directly to these beams as indicated in Fig. 1, the beams having a shelf of ordinary fire brick as shown at 20 for supporting the next course of the lining. This provides a very simple, strong, and effective method of supporting walls the height of which would cause 80 too great a weight of the plastic material. It 85 is obvious that, where desired, air may be circulated through the space 28 for cooling the steel supports.

Referring now to the roof structure which is 90 obviously applicable to arches of the various types used in furnaces, the same type of anchor tile 14 is used for the roof as is used in the side wall lining. As shown by Figs. 1 and 2, we 95 preferably merely slide these tiles onto the I beams 11, and in originally installing the roof we provide a suitable support for the plastic material 12 within the furnace so that it may be pounded down around the anchor tile 14'. These anchor tiles may be spaced sufficiently close together to hold the plastic material until it has 100 been secured or hardened after which the roof becomes substantially one piece of refractory material having the same coefficient of expansion and the same fire resisting qualities throughout its extent.

105 It will be noted that the use of our anchor tile avoids the placing of any metal close to the fire surface where it would be destroyed by the heat. On nine inch walls the metallic lag screw is protected by seven inches of plastic refractory 110 and the insulation. The supporting beam 19 may also be suitably insulated on the heat side without varying the construction.

115 Further the anchor tile as applied does not permit of any wedging action due to the holding of the plastic lining by the tile.

120 It is also believed to be clear that with this anchor tile the plastic lining may be anchored to any type of retaining wall and will protect the retaining wall with an equal amount of protection provided by the plastic lining. Since the material of the lining and of the anchor are the same, any desired number of anchors may be used without affecting the fire resisting qualities of the 125 wall.

130 While we have described the preferred form of our invention, it is evident that various modifications may be made from the details shown and described without departing from the scope of the invention as hereinbefore outlined and as defined by the claims.

135 Having thus described our invention, what we claim as new and desire to secure by Letters Patent is:

1. A furnace wall structure embodying a retaining wall, an originally plastic lining therefor, and means for sectionally supporting and retaining said lining comprising supporting beam means running longitudinally of the wall between the lining and wall, a refractory shelf on said beam means, and refractory anchor means anchoring said lining to said beam means and to said wall.

140 2. A furnace wall structure embodying a retaining wall, an originally plastic lining therefor, and means for sectionally supporting and retaining said lining comprising supporting beam means running longitudinally of the wall between the lining and wall, a refractory shelf on said beam means, and refractory anchor means 145 anchoring said lining to said beam means and to said wall.

150

means anchoring said lining to said beam means and to said wall, said shelf consisting of precast refractory members laid on said beam means.	curing members extending from the outer wall into the ends of the anchors to secure them to the outer wall.	80
3. A furnace wall structure embodying a retaining wall, an originally plastic lining therefor, and means for sectionally supporting and retaining said lining comprising supporting beam means running longitudinally of the wall between the lining and wall, a refractory shelf on said beam means, and refractory anchor means anchoring said lining to said beam means and to said wall, said wall structure having an air duct along side said beam means.	6. A furnace structure having a retaining wall and lining of plastic refractory material having embedded therein pre-cast refractory anchors provided with large spaced ribs on opposite sides between which the plastic refractory is wedged to interlock the anchors and the lining, and securing members for said anchors fixed in the retaining wall and having portions projecting into the lining and interlocking with said anchors in the lining to secure them to the retaining wall.	85
4. A furnace structure comprising a supporting structure, an originally plastic monolithic refractory lining therefor, and means to anchor the lining comprising metallic members secured to the supporting structure, and pre-cast refractory anchors having ribs interlocking with the refractory of the lining in which the anchor is embedded, said metallic members entering the anchors from the end whereby they are protected by the anchors.	7. A furnace structure having a retaining wall and a lining of plastic refractory material having embedded therein pre-cast refractory anchors provided with large spaced ribs on opposite sides between which the plastic refractory is wedged to interlock the anchors and the lining, and securing members for said anchors fixed in the retaining wall and having portions projecting into the lining and interlocking with said anchors in the lining to secure them to the retaining wall, the plastic refractory material being packed around both the anchor and the securing member.	90
5. A furnace structure having an outer wall of non-refractory material and an inner lining of plastic refractory material having embedded therein pre-cast refractory anchors provided with large spaced ribs on opposite sides between which the plastic refractory is wedged to interlock the anchors and the lining together with metal se-	THEODORE KAUFFMAN, JR.
